US00D917458S

(12) **United States Design Patent** (10) **Patent No.:** **US D917,458 S**
(45) **Date of Patent:** **** Apr. 27, 2021**

(54) **NOTEBOOK COMPUTER**

(71) Applicant: **Acer Incorporated**, New Taipei (TW)

(72) Inventors: **Szu-Wei Yang**, New Taipei (TW);
Pao-Ching Huang, New Taipei (TW)

(73) Assignee: **Acer Incorporated**, New Taipei (TW)

(**) Term: **15 Years**

(21) Appl. No.: **29/705,913**

(22) Filed: **Sep. 17, 2019**

(30) **Foreign Application Priority Data**

Mar. 18, 2019 (TW) 108301545

(51) **LOC (13) Cl.** **14-02**

(52) **U.S. Cl.**

USPC **D14/315**

(58) **Field of Classification Search**

(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof in a closed state;

FIG. 9 is another perspective view thereof in a closed state; and,

FIG. 10 is a left side view thereof in a closed state.

The broken lines are for the purpose of illustrating portions of the notebook computer and form no part of the claimed design.

1 Claim, 10 Drawing Sheets
